A. E. HOLADAY.
PRESSURE ROLL RELEASE FOR CLOTHES WRINGERS.
APPLICATION FILED JULY 26, 1916.

1,220,126.

Patented Mar. 20, 1917.

UNITED STATES PATENT OFFICE.

ALBERT E. HOLADAY, OF NAUGATUCK, CONNECTICUT, ASSIGNOR TO THE AMERICAN WRINGER COMPANY, OF WOONSOCKET, RHODE ISLAND, A CORPORATION OF RHODE ISLAND.

PRESSURE-ROLL RELEASE FOR CLOTHES-WRINGERS.

1,220,126.

Specification of Letters Patent.

Patented Mar. 20, 1917.

Application filed July 26, 1916. Serial No. 111,402.

To all whom it may concern:

Be it known that I, ALBERT E. HOLADAY, a citizen of the United States, residing at Naugatuck, in the county of New Haven 5 and State of Connecticut, have invented certain new and useful Improvements in Pressure-Roll Releases for Clothes-Wringers, of which the following is a specification, reference being had therein to the accompanying 10 drawing.

This invention relates to certain new and useful improvements in pressure roll release for clothes wringers and is an improvement on an application for pressure roll release 15 for clothes wringers filed by John F. Hemenway, July 12, 1916, Serial No. 108,909, the object being to provide a release which is exceedingly simple and cheap in construction and one which is so constructed that the 20 movably mounted top bar carrying the pressure screws which release the pressure, is normally held in position within the wringer frame in such a manner that the same can be quickly released in order to allow the top 25 bar to move a predetermined position within the wringer frame.

Another object of my invention is to provide a movably mounted top bar with a resilient retaining member adapted to co-operate with keepers carried by the side bars of the frame, said retaining member being operated by a slidably mounted member having a connection therewith so that when the slidably mounted member is depressed, the 30 ends of the resilient member will be drawn inwardly from under the keepers so as to release the top bar.

Another object of my invention is to provide a novel form of keeper which is so constructed that when the resilient retaining member is drawn inwardly from under the same, the members carried by the retaining member will be caught by the keepers so as to limit the upward movement of the top 40 bar in order to prevent the same from becoming detached from the wringer frame.

Other and further objects and advantages of the invention will be hereinafter set forth and the novel features thereof defined by the 45 appended claims.

In the accompanying drawings,

Figure 1, is a side elevation partly in section of a clothes wringer showing the ap-

plication of my improved construction of pressure roll release thereto;

Fig. 2 is a horizontal section taken on the line 2—2 of Fig. 1;

Fig. 3 is a detail perspective view of a pair of keepers, resilient member, and operating member showing the same separated;

Fig. 4 is a detail view of a slightly modified form of connection for the operating member; and

Fig. 5 is still another slightly modified form of a connection for the operating member.

Like numerals of reference refer to like parts in the several figures of the drawing.

In carrying out my invention I employ a wringer frame 1 which is provided with the usual slotted side bars 2 and 3 in which are mounted the bearings for the roller shafts carrying pressure rolls 4 and 5 which are preferably provided with meshing gears, not shown, inclosed by gear casings. The upper bearings for the upper pressure rolls carrying a shaft are provided with spring supports 6 on which are mounted coil pressure springs 7, carrying plates 8 secured on the ends of a pressure bar 9, said plates being preferably provided with depending studs fitting within the upper portions of the coil spring 7, as clearly shown in Fig. 1.

Slidably mounted within the slotted portions of the side bars 2 and 3, is a top bar 10, which is provided with pressure screws 11 engaging the plates 8 of the pressure bar 9, so as to adjust the pressure on the pressure rolls.

In order to provide means for holding the top bar 10 in a predetermined position within the wringer frame so that the pressure screws 11 carried thereby will exert the proper pressure on the pressure screws through the medium of the plates 8, I provide each of the furcations of the bifurcated bars 2 and 3 with keepers 12 on its inner face, each of said keepers being formed identically alike, and the description of one will be sufficient for all. Each keeper is provided with a horizontally disposed base portion 12' under which is adapted to extend antifriction rollers 13 carried by the end portions of a pin 14, secured in an eye 15, formed on each end of the resilient member 16, which is slidably mounted in guide mem-

bers 17 secured to the top bar 10 as clearly shown in Figs. 1 and 2, so as to prevent the top bar from moving vertically within the wringer frame.

5 The keepers 12 are provided with guideways for the rollers 13 which terminate in hooked portions 12' which are engaged by the antifriction rollers 13 of the resilient member 16 so as to limit the upward movement of the top bar after the rollers 13 have been moved inwardly from under the horizontally disposed portions 12' of the keepers 12.

The resilient member 16 is provided with 15 a centrally disposed bowed portion 18 having a boss 19 extending upwardly therefrom which is provided with a substantially key-hole shaped slot 20 adapted to receive the head 21 of an operating pin 22 which is 20 slidably mounted in a vertical bore 23 of the top bar 10, said spring being connected to the pin 22 before the same is secured in position within the guide members 17, and it will be seen that by throwing the spring 25 obliquely in respect to the under side of the top bar, the head thereof can be forced through the enlarged circular opening of the key-hole shaped slot formed in the boss 19 so as to place the head in position on the 30 narrow portion of the slot in order to detachably connect the operating pin to the resilient member.

In Fig. 4, I show a bowed resilient member or spring 24 having an opening through 35 which the reduced lower end of an operating pin 25 is forced and headed in order to secure the pin to the spring.

In Fig. 5, I show an operating pin 26, having a reduced portion provided with a 40 transverse bore, said reduced portion extending through an aperture formed in the bowed spring 27, and secured in position by a cotter pin 28 extending through the bore of the spring so as to detachably connect 45 the operating pin to the spring.

In the operation of pressure release as herein shown and described, assuming that the wringer is in the position as shown in Fig. 1 with the pressure bar under pressure 50 by the pressure screws carried by the top bar, when it is desired to release the pressure in case of a foreign object being drawn between the pressure rolls 4 and 5, by striking the head of the pin 22, the spring 18 will 55 be forced downwardly so as to contract or draw inwardly the ends of the spring so as to draw the anti-friction rollers 13 from under the horizontally disposed portions 12' of the keepers 12 which allows the top bar 60 10 to move vertically in order to instantaneously release the pressure from the pressure rolls. As the antifriction rollers pass from under the horizontally disposed portions 12' of the keepers 12, the spring 18 65 expands so as to force the antifriction roll-

ers into the guideways of the keepers into such a position that they are engaged by the hooks 12' which prevents the top bar from becoming detached from the wringer frame. This is accomplished by giving the pin a 70 quick blow which draws the ends of the spring inwardly a sufficient distance to allow the top bar to move upwardly, and as the impact on the pin is instantaneously released, the spring normally expands so as 75 to cause the antifriction rollers to travel in the guideway of the keepers.

From the foregoing description, it will be seen that I have provided an exceedingly novel form of pressure release which can be 80 readily attached to any of the well known forms of wringer now in use without changing the construction of the same in any way, as the releasing spring is so positioned that the top bar and the keepers on the side bars 85 can be readily attached without changing the construction.

I claim:

1. A clothes wringer, comprising a frame having pressure rolls and pressure means for said rolls, a top bar movably mounted within said frame having pressure screws for adjusting said pressure means, a resilient member carried by said top bar having laterally projecting members, keepers carried by the side bars of said frame adapted to be engaged by the laterally projecting members of said resilient member for holding said top bar in predetermined position within said frame, and a movable member mounted within said top bar coöperating with said resilient member for moving said resilient member out of contact with said keepers.

2. A clothes wringer, comprising a frame 105 having pressure rolls and pressure means for said rolls mounted therein, a movably mounted top bar carrying pressure screws for adjusting said pressure means, keepers secured to the side bars of said frame provided with guideways terminating in hooks, a resilient member slidably mounted on the under side of said top bar, antifriction rollers carried by the ends of said resilient member coöperating with said keepers for holding said top bar in predetermined position within said frame, and an operating member carried by said top bar coöperating with said resilient member for moving said anti-friction rollers from under said keepers into 110 guideways thereof for releasing said pressure means.

3. A clothes wringer, comprising a frame having pressure rolls and pressure means mounted therein, a movably mounted top bar carrying pressure screws for adjusting said means, keepers carried by the side bars of said frame, a resilient member having laterally projecting members at its ends co-operating with said keepers for holding said 115 120 125 130

- top bar in predetermined position within said frame, means carried by said top bar for moving said resilient member in position to release said top bar, and means for limiting the upward movement of said top bar within said frame. 5
4. A clothes wringer, comprising a frame having pressure rolls and pressure means for said rolls mounted therein, a top bar 19 movably mounted in said frame, keepers secured to the side bars of said frame provided with horizontally disposed base portions and vertically disposed guides, a resilient member slidably mounted on the under side of said top bar carrying antifriction rollers, extending under the base portions of said keepers, and a movable member mounted in said top bar coöperating with said resilient member for moving said antifriction rollers from under the base portions of said keepers into the guideways thereof for releasing said pressure means. 20
5. A clothes wringer, comprising a frame having pressure rolls and pressure means 25 for said rolls mounted therein, a top bar having means for adjusting said pressure, a resilient member for holding said top bar in predetermined position within said frame, a pin slidably mounted in said top bar detachably connected to said resilient member, and means for limiting the upward movement of said top bar within said frame. 30
6. A clothes wringer, comprising a frame having pressure rolls and pressure means for 35 said rolls mounted therein, a movably mounted top bar having means for adjusting said pressure means, a spring slidably mounted on the under side of said top bar, said spring having a centrally disposed bowed portion provided with a boss, said boss having a substantially key-hole shaped slot formed therein, keepers carried by the side bars of said frame, members carried by the ends of said bowed spring coöperating 40 with said keepers, and a pin slidably mounted within the top bar having a head adapted to be interlocked in the key-hole shaped slot of the boss of said spring. 45
7. A clothes wringer, comprising a frame 50 having bifurcated side bars, pressure rolls and pressure means for said rolls mounted in said frame, keepers secured to the upper end portions of said side bars, a movably mounted top bar mounted in said frame carrying 55 means for adjusting said pressure means, guides carried by said top bar, a spring slidably mounted in said guides, members carried by the ends of said spring coöperating
- with said keepers, and an operating member 60 slidably mounted within said bar coöperating with said spring for moving the members carried by the ends thereof out of engagement with said keepers. 65
8. A clothes wringer, comprising a frame having pressure rolls and pressure means 70 mounted therein, a movably mounted top bar carrying members for adjusting said pressure means, keepers secured to the side bars of said frame, a spring slidably mounted on the under side of said top bar, members carried by the ends of said spring coöperating with said keepers, and an operating member slidably mounted in said top bar detachably connected to said spring. 75
9. A clothes wringer, comprising a frame 80 having pressure rolls and pressure means for said rolls mounted therein, the side bars of said frame being bifurcated to form guideways, a top bar slidably mounted in said guideways, pressure members carried by said top bar for adjusting the pressure means, keepers secured to the inner faces of said side bars provided with horizontally disposed portions, and vertically disposed guideways, a spring member slidably mounted on the 85 under side of said top bar, and an operating member slidably mounted in said top bar coöperating with said spring for moving said spring out of engagement with said keepers into the guideways thereof for allowing said 90 top bar to move vertically a predetermined distance. 95
10. A clothes wringer, comprising a frame having pressure rolls and pressure means for 100 said rolls mounted therein, a movably mounted top bar carrying pressure screws secured to the under side of said top bar, a spring slidably mounted in said guideways having a centrally disposed bowed portion, keepers carried by the said bar of said frame, members carried by the ends of said spring coöperating with said keepers, and an operating member slidably mounted in the top bar of said frame coöperating with said 105 spring member for moving the members carried by the ends thereof out of engagement with said keepers to release said pressure means. 110

In testimony whereof I heréunto affix my signature in the presence of two witnesses.

ALBERT E. HOLADAY.
